[57] CLAIM

The ornamental design for an electronic data processor, as shown.

DESCRIPTION

FIG. 1 is a top, front, right side perspective view of an electronic data processor showing my new design;

FIG. 2 is a left side elevation thereof;

FIG. 3 is a rear elevation thereof;

FIG. 4 is a bottom plan view thereof;

FIG. 5 is an enlarged fragmentary view of the upper front portion of the control panel thereof.

FIG. I

FIG.2
